(57) **CLAIM**

The ornamental design for a loudspeaker, as shown and described.

DESCRIPTION

FIG. 1 is a front perspective of a loudspeaker showing my new design.

FIG. 2 is a rear perspective view thereof.

FIG. 3 is a front view thereof.

FIG. 4 is a side view thereof.

FIG. 5 is a rear view thereof.

FIG. 6 is a top view thereof.

FIG. 7 is a bottom view thereof; and,

FIG. 8 is an alternate view thereof, showing the tweeter waveguide assembly rotated into an alternate position with respect to the enclosure.

The broken line showing on the drawing disclosure is for illustrative purposes only and forms no part of the claimed design.
